UNITED STATES PATENT OFFICE.

EDWARD M. ARNOLD, OF PAWTUCKET, RHODE ISLAND.

HOT-WATER HEATER.

SPECIFICATION forming part of Letters Patent No. 430,415, dated June 17, 1890.

Application filed June 26, 1889. Serial No. 315,676. (No model.)

To all whom it may concern:

Be it known that I, EDWARD M. ARNOLD, a citizen of the United States, residing at Pawtucket, in the county of Providence and State 5 of Rhode Island, have invented certain new and useful Improvements in Hot-Water Heaters; and I do hereby declare that the following is a full, clear, and exact description of the invention, which will enable others skilled 10 in the art to which it appertains to make and use the same.

My invention relates to improvements in hot-water heaters, the object being to provide a system of water-ways exposing the 15 greatest possible amount of surface to the action of heat, and I accomplish this by the means illustrated in the accompanying drawings, in which—

Figure 1 is a perspective plan view, in elevation, of furnace; Fig. 2, a vertical section through front and back; Fig. 3, a vertical section through sides; Fig. 4, top view of cross-section on line U V; Fig. 5, same on line W X; Fig. 6, the grate; Fig. 7, the auxiliary grate.

In the drawings, A designates a furnace 20 constructed of suitable material and in a substantial manner. The grate exhibited in the drawings and the manner of mounting the same within the furnace I have described in 25 an application this day filed in the Patent Office, Serial No. 315,673, for which I wish to obtain Letters Patent. These walls A form the outer section of the boiler. The inner section, formed preferably in one piece, is 30 firmly secured to the outer by overlapping joints and fire-proof packing. This inner section, which forms the boiler, is an inclosed steam-tight vessel resting upon and firmly secured to the walls of the ash-pit E.

35 d d d designate vertical parallel water-legs, extending down into the fire-box F. The boiler consists of a series of these vertical parallel water-legs, d, Fig. 3, designating one of these legs, being a thin envelope filled with 40 water, extending from side to side and arched over the fire-box F. This method of construction of thin water-legs is employed, having air-spaces s s, &c., Fig. 2, between legs d, to provide the greatest possible exposure of 45 boiler-surface to the action of the heat. This boiler is also constructed in such a manner as

55 to form an inner face G in the upper part thereof, to allow the hot air to circulate freely through the upper part of said boiler. In the lower part of this face I place a metal V-shaped deflector, designated as H, Fig. 4, by means of which the heat is deflected against the sides and thence arises to the top of the boiler.

h designates a passage, by means of which the heat is conducted to the draft-pipe P. 60

P designates a draft-pipe, fitted into the rear wall of the furnace by a collar p. The collar p extends within the boiler and is slit on the upper side from the pipe to the side of the furnace, these ends being then spread 65 out to form a passage leading to the passage h.

R designates a section of pipe leading from the ash-pit E to the collar to allow the escape of dust by means of the dampers r and r'.

T designates the conducting-pipe connecting with the boiler and radiators. 70

t designates a return-pipe, and t' a faucet for drawing off the water. Water can be introduced into the boiler by means of this pipe.

Water being introduced into the boiler and 75 the fire started, the hot air arises in the direction indicated by the arrow 1. The hot air circulates freely until reaching the position shown by cross-section on the line W X. Here

the hot air, being deflected by the V-shaped 80 deflector, passes in the direction indicated by arrow 2 up through each one of the spaces, h', &c., being continuations of the spaces s, &c., to the top of the boiler, and thence to the 85 passage h, which leads, as described, to the collar p and the draft-pipe P. It will be observed that by means of my construction and employing an inner face, as described, and the V-shaped deflector, thus practically forming a diaphragm into which the heat is deflected, and caused to circulate freely around the upper part of the boiler, and by using comparatively thin water-legs extending from the upper part down to the fire, leaving sufficient spaces for hot air between the same, 90 every square foot of the boiler is exposed to to the heat, and by this construction attaining all the advantages of a tubular boiler and yet being able to make the same in one piece. These advantages it is unnecessary to enlarge 95 upon, as they are well-known to all conversant with steam-boilers. 100

My devices can be employed to equal advantage for converting water into steam and using steam as the heating agent.

What I claim, and desire to secure, is—

- 5 1. In hot-water heaters, the combination of a fire-pit suitably mounted and an inclosed steam-tight vessel consisting of a series of vertical water-legs extending down to the fire-pit, arching over the fire and extending down 10 the sides thereof, having spaces between said legs for circulation of the hot air, and an inner face G in the upper part of said boiler forming an inner flue, substantially as described.
- 15 2. In hot-water heaters, the combination of

the fire-pit, the steam-tight inclosed boiler consisting of vertical water-legs extending down to the fire, having spaces between said legs, and an inner face G in the upper part thereof, provided with a V-shaped deflector 20 mounted in the lower part of said face, and a passage leading to the draft-pipe, all substantially as and for the purpose described.

In testimony whereof I have hereunto set my hand in the presence of two subscribing 25 witnesses.

EDWARD M. ARNOLD.
In presence of—

EDWARD W. BLODGETT,
W. W. BLODGETT.
